METHOD OF THROWING SILK

Maurice Albert Salembier, Jr., Plandome, N. Y.

Application May 13, 1935, Serial No. 21,079

6 Claims. (Cl. 117—21)

This invention relates to a new and improved method of silk throwing and more particularly to an improved method of producing a continuous multiple strand silk thread.

5 The art of silk throwing includes the steps of winding, doubling, twisting and usually, coning, to form a suitable silk thread from raw skein silk. Of these operations, certain ones, particularly doubling, have been the source of multiple strand knots which are highly objectionable not only in waste of material and delay in throwing, but they are especially objectionable in the final product and its uses.

10 It is the principal object of my invention to provide an improved method of throwing silk yarn by which I produce continuous lengths of silk yarn of multiple strand type having no knots common to all strands, my method including the step of tying single strand knots in case 15 of breaks or runouts in the separate strands.

15 Another object of my invention is to provide an improved method of throwing silk which includes the steps of stopping multiple strand thread in the doubling machine prior to the point of doubling or twisting, in case of a single 20 strand break, and tying the single strand to its appropriate supply without destroying the continuity of the other strands.

25 Another object of my invention is to provide an improved method of throwing silk to form a multiple strand thread by winding multiple strands from a plurality of separate strand bobbins which includes the step of stopping the thread between the creel and point of twist if a strand breaks, 30 tying a single end knot in the broken strand without drawing the completed thread back off the receiving bobbin and subsequently uniformly tensioning and twisting the knotted and unknotted strands.

35 A still further object of my invention is to provide an improved method of throwing natural silk to form a continuous multiple strand, multiple twist thread having uniform texture and no knots common to all strands in packages of 40 the order of six ounces or larger which comprises the steps of winding single strand bobbins having a length approximately equal to the length of the single strands in the final package, feeding multiple strands from a plurality of such bobbins to 45 a single receiving bobbin to form a doubled thread, stopping said feed, if a single strand breaks, before the broken strand reaches a point of doubling or twisting, tying a single strand knot in the broken strand and the single strand from 50 the winding bobbin, twisting the knotted and

unknotted strands, and transferring a single bobbin of twisted and doubled thread to fill a single final package.

5 Further objects and advantages of my invention will appear from the following description thereof, taken in conjunction with the attached drawing which is a diagrammatic elevational view of certain parts of a throwing machine on which my new process may be carried out.

10 One of the principal sources of knots common to all strands in a multiple strand thread is in the step of doubling or forming the multiple strand thread having two or more strands from a plurality of the single strands. Doubling is not limited to two strand thread but is used in its 15 commercial sense of forming multiple strand thread of any desired number of strands. This operation is commonly performed on a combined doubler-twister type of machine which forms and winds the multiple strands and at the same time 20 gives the multiple strands a certain predetermined twist. Such machines are especially suitable for throwing silk yarn for hosiery tram as such product is a multiple strand thread commonly having relatively few turns per lineal inch. 25 Such machines are also frequently used in the preliminary steps of forming other threads such as crepes, etc., which although of a higher twist, are initially formed into multiple strands on the 30 doubler-twister type of machine and subsequently given a final twist on a twister.

35 I have diagrammatically shown parts of a doubler-twister type of machine to better illustrate the steps of my improved process of throwing silk yarn, although I am not limited to such 40 machines as my process can be carried out on any type machine adapted to form multiple strand thread. In general such machines have a creel or pin rail 10 which is provided with a number of pins 11 to support the desired number of single 45 strand bobbins 12. It is, of course, to be understood that different types of thread require a different number of strands, hosiery tram, for example, varying from two to twelve or more depending on whether used for sheer or service 50 weight hosiery, and for leg or welt or foot portions.

55 Considering as a special example, throwing of a four strand, low twist thread, four single end yarn bobbins 12 are placed on the respective pins 55 11 and the separate ends *a*, *b*, *c* and *d* are drawn through the eyes of the individual drop arms 14, and then the separate strands are gathered by the gathering eye 16. The single thread then usually passes around certain feed rolls 18 or

other tensioning devices, through guide eye 19 and then to the receiver bobbin 20, through the guide eye 22 on the traverse or ring rail 24.

As is well known, the receiving bobbin 20 is rotated at a desired speed to properly wind the doubled multiple strand thread and the feed rolls 18 which are driven at a predetermined speed relative to that at which the receiver bobbins are operated act as take up rolls or tension devices. The feed rolls 18 in this type of machine determine the amount of tension on the doubled thread and the relative rate of rotation of the feed rolls 18 and the receiver bobbin 20 determines the number of twists the thread is given 15 per inch.

I do not show in detail the operation of the stop mechanism, but it will be understood that a suitable stop mechanism is placed in operation to stop the feed rolls 18 and the receiving bobbin 20 by the dropping of a drop arm 14 due to run-out or exhaustion of the supply on a bobbin 12, or due to waste or other matter catching in the eyes of the drop arm 14 which breaks a strand. It will be clear that a break or run-out in the 25 strand will occur between the bobbins on the creel or pin rail 10 and the eye of the drop arms 14. As illustrative of the operation of my device, I have shown one of the strands *a* of the thread broken and the appropriate drop arm in 30 stopping position.

It is necessary in forming multiple strand thread to always have the same number of strands in the thread at every point as less than the full number of strands would cause a re-35 jection of the yarn as totally defective. A lesser number of strands was frequently partially wound on the receiving bobbin however as the thread passes so rapidly (receiving bobbins frequently run 4500 revolutions per minute) that even if the 40 drop eyes operated the usual stop mechanism, it would still not prevent some of the lesser number of strands from passing through the guide eyes and on into the receiving bobbin. It has been the practice of throwsters to sever all the 45 unbroken strands when one strand broke, the operators either breaking all the other strands by hand, or automatically operated means connected to the stop motion mechanism were provided to accomplish this result. Some of the 50 wound thread was then drawn back from the receiving bobbin until the operator found the desired number of thread strands after which a knot common to all strands was tied, the knot trimmed, and the trimmings and slack discarded 55 to waste. The thread drawn back from the bobbin and trimming of the knots was a source of considerable waste, and the knot was highly objectionable.

In accordance with my improved method of 60 throwing silk and in operating the machinery used for forming silk thread, I find that I can eliminate a substantial amount of waste heretofore occasioned in tying multiple strand knots and avoid the delay due to drawing of thread 65 back from the receiving bobbin. I also provide a superior product which has no knots common to all strands and which is therefore a far superior product to that heretofore produced. As one 70 step of my improved method of throwing silk, I stop and incomplete thread between the creel and the point of twist so that I can tie a single strand knot without untwisting or drawing the thread back from the bobbin. As shown in the drawing, this region of separated strands is generally indicated at 75. Stopping the thread in this space

may be accomplished by various different forms of machinery, it being essential, however, that in case of a broken strand, the receiving bobbin and feed rolls stop before the point of break in the strand becomes twisted in other portions 5 of the thread.

As a second step in my improved method of throwing silk, I then tie a knot such as 26 in the broken strand only, so that the knot is adjacent continuous portions of the unbroken 10 strands and is therefore relatively small in comparison with a knot common to all strands. In the subsequent twist generally given the thread the single strand knot blends in and becomes almost totally invisible. I find that the single 15 strand knots will pass practically all knot detectors, carriers or needles which will pass the majority of the unknotted thread.

Inasmuch as I stop the thread prior to the point at which the broken strand becomes twisted 20 with the unbroken strands, it is unnecessary to draw any wound thread back from the receiving bobbin to count ends as formerly required, and it is unnecessary to make any visual inspection other than merely to join the portions of 25 the broken strand. A break in one strand will be instantly noticeable and with the other strands continuous, the mere tying of the broken strand will in itself be an inspection to show that all 30 ends are present in the thread.

After the knot is tied in the broken strand, the spindle is restarted and as the knot is between the single strand bobbins 12 and the feed rolls 18 the tensioning of the knotted and unknotted strands will be uniform. Uniform 35 tensioning improves the elasticity of the thread which is of major importance in many products such as hosiery which require a high elasticity characteristic.

As a further step in my improved process I 40 fill each receiving bobbin 20 with an amount of continuous doubled thread sufficient to completely fill the final package whether it be a cone or of other type. Coning from bobbins having full equivalent amounts of yarn saves a substantial 45 amount of time and eliminates the usual knots and variable tension in the coning of three ounce and larger packages. The elimination of knots is also very important in coning because it often happens that different bobbins will have 50 slightly different types of thread as hereinafter described and I entirely avoid such difficulties.

Although I am not so limited, I also find it highly desirable to use single end bobbins having a continuous single strand equal in length 55 to the single strands of the desired final package. By this I mean that I provide a single end bobbin which will not run out in forming the desired receiving bobbin 20 of the double thread. I also use bobbins in the other machines including 60 twisters, etc., which will hold the entire supply for the finished package. Although this has been practiced to some extent in making smaller packages of silk, it has been customary in making packages of three ounces and over and especially, 65 the eight ounce package to use the customary small bobbins which required joining different lots of thread. I avoid this entirely by forming a continuous strand of twenty thousand yards or more in which some thread strands are continuous 70 at every point.

Tying of single strand knots makes it unnecessary to carry out the usual redraw operation which was commonly required for inspection, cleaning and elimination of hidden knots. In 75

addition, spool for spool transfers of large package quantities from doubler-twister to twisting machines and from the twisting machines to the coning machine is especially beneficial with high 5 twist threads such as crepe, inasmuch as there can be no slack twist which formerly required the loss of several yards of material at each knot. With single strand knots the twist is continuous and redrawing being eliminated there is a much 10 higher percentage of thread available for coning or other packaging.

Ordinarily there is no other knot or break at the same point, although it is to be understood that single end bobbins usually carry yarn which 15 has been knotted in one or more places, and it is possible that a winding knot, for example, may occur at a point adjacent a new break during the doubling operation. While I prefer not to tie other than single thread knots, I find that if 20 not more than two-thirds of the strands of four strand thread or greater are tied together at any one point, this may not be objectionable from the standpoint of future use of the double thread. In a four strand thread, for example, I have 25 tied a knot common to two strands and in a five strand thread, I have tied a knot common to as many as three strands without objection. Tying more than this frequently causes subsequent difficulty and is to be avoided.

30 I find that my improved method of silk throwing saves a very substantial amount of the total throwing costs, reduces labor and machine costs and brings about a very substantial saving in waste. Inasmuch as I tie a knot in a single 35 strand only, there is a saving of at least three-fourths that heretofore lost in tying knots common to all strands in a four strand thread and there are other savings in time and material by not drawing thread back from the receiving bobbin. The gross saving in waste alone can be 40 reduced more than one-half by my method of tying knots which represents a very substantial advantage.

A multiple strand thread having no knots common to all strands is a premium product and 45 highly desired by the using trade. For hosiery tram, it is particularly satisfactory in that as there are no knots common to all strands, press-offs due to the knots catching in the needle or 50 carrier or untying are eliminated, and the final product has none of the knots which were formerly so conspicuous as to cause rejects and reclassification. My larger package product available by my improved method of throwing is 55 also especially suitable for hosiery tram as an eight ounce package will make approximately one dozen pairs of hosiery leg portions, depending on the denier and strands of the thread and with no common knots, I can eliminate the losses due to the three or four knots which formerly existed in this size package.

Furthermore, having no knots common to all 60 strands there is no opportunity of joining mismatched threads. As is well known, threads of 65 the same denier size classification are not uniform in diameter and the variation is such that in certain woven cloths as well as in some knitted products the change in tint, diameter and nature may be very conspicuous and highly objectionable. This is especially noticeable during 70 subsequent dyeing. There is no point in my thread at which there is less than one continuous strand and preferably only one strand is knotted at any one point so that any difficulty 75 due to the possible variation in joining threads

from different bobbins is entirely eliminated. I also avoid hidden knots in the coning operation and prevent unravelling or catching of thread bunches due to knots accidentally occurring on the side of the cone which commonly causes considerable difficulty in the using machine during 5 knitting, weaving, etc.

I have referred to my method of throwing as relating to silk and I mean by that, natural silk which is well known to be a relatively small size fiber although varying in denier, such silk being elastic, 10 relatively strong and commonly formed into a multiple strand thread to form a suitable product. There are other fibers, however, such as artificial 15 silk, to which my invention is applicable where such fibers have similar characteristics of elasticity, strength, size and necessity of doubling.

While I have described a preferred form of embodiment of my invention, I am aware that other modifications may be made thereto and I 20 therefore desire a broad interpretation of my invention within the scope and spirit of the description herein and of the claims appended hereinafter.

I claim:

1. The method of producing a natural silk yarn having a continuous length of at least twenty thousand yards which comprises the step of winding a continuous length of a single strand of at least twenty thousand yards, subsequently forming multiple strands on a spool adapted to contain twenty thousand yards of the multiple strand thread, and tying single strand knots at single strand breaks prior to the formation of the multiple strand thread. 35

2. The method of producing a continuous twist- 40 ed multiple strand thread having a length of at least twenty thousand yards, of smooth texture and having no knots common to all strands which comprises winding a plurality of single strands of at least twenty thousand yards, doubling said strands, tying breaks in single strands independently of other strands, twisting the tied and continuous strands, winding a single bobbin with a continuous thread of the desired length, subsequently setting the twist in said thread and finally making a complete spool for spool transfer of 45 said thread to form a final package.

3. The method of making a continuous multiple strand natural silk organzine yarn of a 50 length equivalent to an eight ounce mass and having in the range of two to twelve strands of ten to twenty denier which includes the simultaneous doubling and twisting of a plurality of silk strands into a single yarn on a doubler-twister machine, tying single strand knots in a 55 broken strand in case of a break or run-out, uniformly tensioning the broken and unbroken strands, subsequently uniformly twisting the multiple strand yarn from end to end after the 60 single strand knots have been tied and finally setting the twist of the yarn.

4. The method of producing a natural silk 65 yarn having a continuous length of at least twenty thousand yards which comprises the step of winding a plurality of continuous lengths of single strands of at least twenty thousand yards, subsequently doubling and twisting said single strands and winding said strands on a spool adapted to contain twenty thousand yards of the 70 multiple strand thread, tying single strand knots during the doubling-twisting operation at single strand breaks, and subsequently making complete spool for spool transfer of the yarn in further throwing steps. 75

5. The method of making multiple strand natural silk yarn equivalent in length to a weight of six or more ounces, which comprises winding a plurality of continuous lengths of single strands of natural silk equivalent to the length of strands in the finally desired package, subsequently doubling and twisting said single strands on a doubler-twister machine, tying single strand knots in said separate strands in case of a break or run-out, winding said multiple strand yarn on a single spool adapted to contain all of the yarn of the final package, transferring said yarn completely from one spool to another in a twisting machine and twisting said yarn during the transfer and subsequently packaging said twisted yarn by completely transferring the twisted

yarn to a package containing the entire spool of twisted yarn.

6. The method of throwing natural silk which comprises feeding from each of a plurality of single end bobbins, a single strand equal in length to the strand of the final package, tying single strand knots at a break or run-out to maintain the continuity and independence of the strand, twisting the knotted and unknotted strands under uniform tension, winding the twisted and doubled thread on a receiving bobbin and subsequently forming a full package from the single receiving bobbin in spool for spool transfer.
